UNITED STATES PATENT OFFICE.

GUSTAV KORITTK, OF NEW YORK, N. Y.

SAFETY-STIRRUP.

1,102,762.

Specification of Letters Patent.

Patented July 7, 1914.

Application filed December 22, 1913. Serial No. 808,187.

To all whom it may concern:

Be it known that I, GUSTAV KORITTK, a subject of the German Emperor, and resident of the city of New York, in the county of New York and State of New York, have invented certain new and useful Improvements in Safety-Stirrups, of which the following is a specification.

The present invention relates to stirrups, and more particularly to safety stirrups which are constructed with a view to prevent the rider's foot from hanging or catching after dismounting, or in case the rider is thrown.

One of the objects of the invention is to provide a device of this type, which is simple in construction, efficient in operation, and which can be manufactured on a commercial scale, or in other words which is not so difficult to produce as to be beyond the reasonable cost of such an article.

With these and other objects in view, which will more fully appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:

Figure 1 is a front elevation of a safety stirrup constructed in accordance with the present invention; Fig. 2 is a side elevation thereof; Fig. 3 is an enlarged front elevation of a portion of the same, certain parts being broken away to more clearly show the interior construction; Fig. 4 is a section taken on line 4-4 of Fig. 3; and Fig. 5 is a similar view, the parts being shown in positions differing from those in Fig. 4.

Broadly speaking, the stirrup is made of two sections, that is to say a strap member and a foot receiving member, said two parts being provided with coöperating means which lock the same together against longitudinal and lateral movement, but permit the foot receiving member to automatically unlock itself from the strap receiving mem-

ber when the former is forcibly tilted in either direction out of the plane of the strap member.

Referring now to the drawings, there is shown a stirrup formed of two members 10 and 11, the member 10 being the strap member and the member 11 the foot receiving member. The strap member is made in the form of a flat plate, that is provided upon its upper end with an eye 12 for the reception of the usual strap depending from the saddle, said strap, however, is not shown in the drawings. From the lower end of said plate extends downwardly a lug 13, the outer edge 14 of which forms a continuation of one of the longitudinal edges of the plate. With this lug is made integral an inwardly running projection 15, that extends beyond the longitudinal center line of said plate. In the edge 14 of the lug is provided a notch 16, for a purpose hereinafter to be described. From the opposite side of the lower end of the plate extends downwardly a shoulder 17.

The foot receiving member 11 of the stirrup is of the usual loop form, and has at the upper portion of the loop a hanger member 18, the edge 19 of which is arranged flush with the edge 20 of the plate of the strap member. From the hanger member extends inwardly a projection 21, that is adapted to rest upon the projection 15 of the lug 13, a notch 22 being formed in the edge 19 of the hanger member for receiving the shoulder 17 of the plate of the strap member. Upon the loop of the foot receiving member is furthermore provided a shoulder 23, that is seated in the notch 16 in the edge 14 of the lug 13. The lower end of the projection 21 is tapered, as shown at 24, upon both of its sides toward the projection 15. On both faces of the plate of the strap member are disposed springs 25, preferably made of two or more leaves superposed, said springs being attached to the strap member by screws 26, or otherwise. The inner leaves of the springs extend down beyond the shoulder 23 of the foot receiving member.

In assembling the stirrup, first the springs 25 are fastened to the strap member. One of the springs is then forced out of the plane of said strap member, and the hanger member of the foot receiving member forced at an angle below the said outwardly bent spring upward until the lower edge of the

tapering end 24 of the projection 21 is brought to rest on the projection 15 of the plate of the strap member. When in this position, the hanger member is forced into 5 the plane of the plate of the strap member, whereby the shoulder 17 is seated in the notch 22 and the shoulder 23 in the notch 16 above described. Upon ordinary conditions, the direction of the force, due to 10 the presence of the foot of the rider in the stirrup, is substantially longitudinal to the foot receiving member and the strap member, and for this reason the lower edge of the tapered end of the projection 21 rests 15 upon the projection 15 of the lug 13. The shoulders 17 and 23 on the strap member and the foot receiving member, respectively, prevent a disengagement of these two parts in lateral directions, the springs preventing 20 a disengagement in a horizontal plane, that is to say in a direction at right angles to the lateral direction. Should the rider fall from the saddle and the foot be passed through the stirrup and be locked therein, 25 the foot receiving member will assume a position approaching the horizontal. Under these conditions, the lower edge of the tapered end 24 of the hanger member 18 is brought to the outer face of the projection 15 (Fig. 5), the springs on the outer face 30 of the strap member obviously yielding. A pull on the foot receiving member causes then the latter to slide on one of the tapering sides of the projections 21 off of the projection 15, whereby the two members of 35 the stirrup are disengaged. Thus if the foot of the rider be locked in the foot member, the latter will unlock from the strap

member almost instantly, and the dragging of the rider is thus avoided. 40

It is to be observed that, inasmuch as both sides of the projection 21 are tapered and since there are springs provided upon both faces of the plate of the strap member, the foot receiving member can be swung toward 45 either face of the plate of the strap member and can thus be disengaged on either side of the strap member from the latter. By reason of this construction, it is possible to use the stirrup on either side of the saddle 50 indiscriminately.

What I claim is:

A stirrup comprising a strap member in the form of a plate provided with a downwardly extending lug having an inwardly extending projection, a foot receiving member formed with a hanger having an inwardly extending projection adapted to rest on the projection of said lug, the lower portions of the faces of the projection of said hanger being tapered toward their lower edges, springs attached to said strap member normally maintaining said projections in engagement with each other but yieldable to an abnormally directed force, and 60 shoulders on said strap member and said foot receiving member for preventing a disengagement in lateral directions of said two members. 65

Signed at New York, in the county of 70 New York, and State of New York, this 17th day of Nov., A. D. 1913.

GUSTAV KORITTKE.
